CLAIM

The ornamental design for a wheel base assembly for a cart having a braking mechanism, as shown and described.

DESCRIPTION

FIG. 1 is a front perspective view of a wheel base assembly for a cart having a braking mechanism showing our new design;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

1 Claim, 8 Drawing Sheets See application file for complete search history.
